UNITED STATES PATENT OFFICE.

MILTON C. STERN, OF DAYTON, OHIO, ASSIGNOR TO THE EGRY REGISTER COMPANY, OF DAYTON, OHIO, A CORPORATION OF OHIO.

MANIFOLDING DEVICE.

1,247,891.

Specification of Letters Patent. Patented Nov. 27, 1917.

Application filed April 9, 1915. Serial No. 20,103.

To all whom it may concern:

Be it known that I, MILTON C. STERN, a citizen of the United States, residing at Dayton, in the county of Montgomery and 5 State of Ohio, have invented certain new and useful Improvements in Manifolding Devices, of which the following is a specification, reference being had therein to the accompanying drawing.

10 This invention relates to manifolding devices and more particularly to that type of manifolding devices known as autographic registers.

15 The object of this invention is to provide a simple organization of parts whereby the webs of paper can be positively and efficiently advanced without the disarrangement and tearing thereof.

20 In the accompanying drawings Figure 1 is a perspective view, partly broken away, of an autographic register embodying my invention; Fig. 2 is a longitudinal sectional view of the same; and Fig. 3 is a transverse sectional view taken through a portion of 25 the writing table and one of the feeding devices.

25 In these drawings I have illustrated one embodiment of my invention and have shown the same as applied to an autographic register, the main features of construction of which are well known. It will be understood, however, that this particular machine is chosen for the purpose of illustration only, and that the invention is applicable, either in its present form or in 35 a modified form, to manifolding devices of various kinds.

30 As here illustrated, the manifolding device, or register, comprises a base 1 provided with upwardly extending side walls 2 which carry at their upper edges a supporting plate 3 which, in the present type of machine, constitutes a writing table. Mounted beneath the writing table and between the side walls 2 is a plurality of webs 4 which are preferably in the form of rolls, as indicated at 5, and are here shown as mounted on shafts or rods 6 which are mounted at their opposite ends in the 45 respective side walls or frame members 2. These webs of paper are carried rearwardly about a guide 7, which is common to the several webs, and thence about separated guides 8 and 9, the guide 9 for the innermost web being in the form of a roller hav-

ing circumferential ribs 10 which constitute guides to maintain the webs against lateral relative displacement. The webs are carried forward over the supporting plate or table 3 in superimposed relation, and have interleaved between them carbon sheets 11 which, preferably, extend lengthwise of the writing table and are here shown as mounted on rolls 12 arranged at the rear of the writing table between the positions occupied by the several webs as they pass about the guides 8 and 9. The strips of carbon paper are carried from the rolls 12 forward over the writing table between the respective webs of paper. The upper part of the 60 manifolding device as a whole is covered by a top plate or cover 13 which is hinged at one end to the side members 2, as shown at 14, and is held in its closed position by means of latches 15 arranged to engage the 65 same at that end opposite its point of connection with the side members 2. This top plate 13 is provided with an opening 16 through which is exposed a portion of the writing table. These manifolding devices 70 are used very extensively for preparing bills of various kinds, and this opening 16 is of such a size that it will expose the printed form on which the writing is to appear.

75 To cause the several webs to be fed lengthwise of the writing table in unison, and to maintain the same against relative displacement during the feeding operation, which would result in the forms on several webs being thrown out of alinement, I have provided the machine with feeding devices arranged along the opposite sides of the exposed portion of the writing table and having parts adapted to simultaneously engage the several webs of paper and move the same 80 lengthwise of the writing table. These feeding devices comprise longitudinal movable members which are here shown as endless belts such as sprocket chains 17. These endless feed members pass about rotatable supports, such as sprocket wheels 18 and 19, which are arranged at the respective ends of the writing table and which are mounted on shafts 20 and 21, journaled in the side members 2 of the frame. These endless 85 feeding members are provided with projections, here shown as prongs or pins 22, which are adapted to extend through the several webs of paper and thus hold the same in fixed relative positions. As here shown, 90

95 110

these projections are in the form of tapered pins, and the several webs are provided along each of their edges with a series of holes 23, spaced equal distances apart. The 5 holes in each web are formed in exactly the same relation to the printed forms as in the other webs, and, consequently, when the pins 22 extend through the corresponding holes in the several webs, these forms are held in 10 exact alinement, both during the writing operation and during the feeding operation. The number of pins or projections employed may vary, according to circumstances, but, I have here shown a pin on each alternate 15 link of the sprocket chain 17. Means are preferably provided to prevent the sagging of the endless feeding members between the two rotary supports, as such sagging might withdraw the pins from their openings and 20 either permit the webs to have relative movement or tear the webs in the feeding operation. In the present instance, the writing table is provided in each of its lateral portions with longitudinal slots 24 which are 25 located just beyond the edges of the exposed portion of the table, and in which slots the respective feeding members 17 travel. As here shown, the endless feeding members or chains 17 are arranged in the slot with their 30 upper surfaces approximately flush with the writing table so that the pins will project above the surface of the writing table but the body of the chain will not displace the webs of paper with relation to the writing table. To support the feeding members and 35 prevent them from sagging I have provided the two slots or openings 24 with trough-shaped supports or guides, 24^a, which are secured to the under side of the writing table 40 and form grooves in which the feeding members travel and which support the feeding members throughout the length of the exposed portion of the writing table. It is also desirable that some means should be 45 provided to hold the webs of paper in engagement with the projections on the feeding device and prevent their accidental displacement. To this end, I have provided the top plate 13 with depending portions or 50 ribs extending along the opposite sides of the openings 16 and arranged to engage the uppermost web of paper along the rows of openings therein, and thus press the several webs of paper downward onto the writing 55 table and prevent them from moving away from the feeding members and becoming disengaged from the projections 22 thereon. Preferably, there is one of these ribs on each side of each row of openings, and, in 60 the present instance, I have secured to the top plate 13, on each side of the opening therein, a narrow plate or strip of metal 25 provided with a longitudinal groove 26, which groove is preferably V-shaped in 65 cross section. This groove is arranged im-

mediately above the position occupied by the webs of paper, and is adapted to receive the upper ends of the projections 22 which project beyond the upper web of paper. Those portions of the plate on either side of the 70 groove bear upon the upper web of paper and thus hold the same below the upper ends of the projections. In this manner the grooved strips not only serve to hold the paper in proper operative relation with the 75 projections on the feeding members, but also serve to guide the feeding members themselves and prevent their lateral displacement. Feeding movement may be imparted to the endless feeding members in any suitable manner, but, in the present instance, I have caused the shaft 21, which carries the forward rotary supporting members 18, to project beyond the side of the machine, as indicated at 27, and have provided the same 80 with a handle 28, by means of which the supporting members 18 may be rotated and forward or feeding movement imparted to the endless feeding members. The feeding device is automatically stopped at the end 85 of each feeding operation by means of co-operating pins carried by the frame member 2 and the handle 28, respectively, the handle and the pin mounted thereon being movable axially in order to disengage this pin from 90 the pin upon the frame member 2. As shown in dotted lines in Fig. 1, a stopping device is provided to prevent the rearward movement of the feeding mechanism at the end of a complete operation. This device 95 comprises a cam stop 30 rotatable with the shaft 21 and a co-operating pin 31, the pin 31 being slidably mounted in a bearing 32. It will be noted that the carbon webs 11 are so arranged that they will not be fed forward along with the webs of paper. To this end the carbon webs are of less width than the webs of paper, being substantially equal in width to the opening 16 in the cover plate, which defines the exposed portion of the 100 writing table. Consequently, they are not engaged by the feeding devices and the frictional engagement between the webs of paper and the carbon webs is not sufficient 105 to carry the carbon along with the paper. If desired, a frictional resistance may be offered to the movement of the rolls 12 to insure their being held against accidental unwinding movement. In order that the lower parts of the feeding members or chains 110 may not sag and come in contact with the webs of paper beneath the writing table, I have provided a guard plate 29 which is supported by the side members 2 of the frame beneath the feeding members, and 115 serves to support the lower stretches of the endless feeding members above the webs of paper, and to prevent the webs of paper 120 from coming in engagement therewith. The operation of the device will be read- 130

ily understood from the foregoing description, and it will be noted that the feeding devices engage the several webs of paper along both sides of the writing table in such a manner as to hold the same firmly against displacement during the writing operation, and that these feeding devices remain in engagement with the several webs of paper to hold the same against relative displacement during the feeding movement. The mechanism is of an exceedingly simple construction, comprising a very few parts, and having these parts of such a strong, durable character that they will not be readily broken or disarranged. Further, it will be noted, that there is no feeding mechanism interposed between the forward ends of the exposed portion of the writing table and the forward ends of the cover plate 13, which forms the cutting edge along which the webs of paper are torn after they have been fed from the machine. Consequently, this forward portion of the cover plate comprises a narrow bar only and, therefore, it is necessary to allow only a narrow margin at the edge of the bill to enable it to extend past this bar.

While I have shown and described one embodiment of my invention, it will be understood that this has been chosen for the purpose of illustration only, and that I do not desire to be limited to the details of construction shown and described, for obvious modifications will occur to a person skilled in the art.

Having thus fully described my invention, what I claim is new and desire to secure by Letters Patent, is:—

1. In a device of the character described, a writing table to support a web of writing material, web feeding devices mounted at each side of said table, said web-feeding devices having pins thereon extending above said table adapted to engage the web of writing material, a cover positioned above and adjacent to said table, and means immovably fixed to said cover and located above said table and said pins to keep said web in engagement with said pins and against the writing table.

2. In a device of the character described, a support for a web of writing material, elongated web feeding devices comprising pins and extending lengthwise along each side of said support, said feeding devices being positioned with their pins only extending above the support for the web, and means mounted above the support and extending along each side thereof and over the pins for retaining the web in engagement with the pins and against the support.

3. In a device of the character described, a support for a web of writing material, longitudinally extending slots in said support, elongated web feeding devices mount-

ed in alinement with said slots and extending lengthwise thereof, said web feeding devices having pins thereon extending above the support for the web and adapted to engage said web, and longitudinally extending means above and adjacent to said support and pins, said means having clearance spaces therein embracing the pins, whereby said web is retained in engagement with said pins.

4. In a device of the character described, a writing table to support a plurality of superimposed webs, elongated web-feeding devices mounted at each side of said table and extending lengthwise thereof, said web-feeding devices having pins thereon adapted to engage the webs of paper, a member positioned above and adjacent to said table, and longitudinally extending means immovably attached to said member at each side thereof and adjacent said pins, said means having clearance spaces therein embracing said pins, whereby the webs of paper are held in engagement therewith.

5. In a device of the character described, a table to support a plurality of superimposed webs of paper, a cover plate extending over said table and having an opening to expose a portion of the uppermost web supported by said table, endless feeding members arranged for movement lengthwise of said table beneath said cover plate on the opposite sides of the opening therein, said endless feeding members each having a series of pins to engage the several webs of paper at a plurality of points along the sides of said opening in said cover plate, and means carried by said cover plate to retain said webs of paper in engagement with said feeding devices, and means to actuate said feeding devices.

6. In a device of the character described, a table to support a plurality of superimposed webs of paper, a cover plate extending over said table and having an opening to expose a portion of the uppermost web supported by said table, endless feeding members arranged for movement lengthwise of said table beneath said cover plate on the opposite sides of the opening therein, said endless feeding members each having a plurality of projections arranged at intervals along the opposite sides of the opening in said cover plate, and each adapted to extend through the several webs of paper on said table, ribs depending from said cover plate on the opposite sides of said opening to retain the several webs of paper against movement away from said feeding members, and means for actuating said feeding members.

7. In a device of the character described, a table to support a plurality of superimposed webs of paper, a cover plate extending over said table and having an opening to expose a portion of the uppermost web sup-

ported by said table, endless feeding members arranged for movement lengthwise of said table beneath said cover plate on the opposite sides of the opening therein, said 5 endless feeding members each having a plurality of projections arranged at intervals along the opposite sides of the opening in said cover plate, and each adapted to extend through the several webs of paper on said 10 table, said cover plate having depending portions arranged in opposite sides of said opening and extending lengthwise thereof, each of said depending portions having a groove arranged to receive the upper ends 15 of the projections on the respective feeding members, and means for actuating said feeding devices.

8. In a device of the character described, a main frame, a table carried by said frame, 20 a plurality of rolls of paper supported by said frame beneath said table, and having the end portions of their webs arranged

above said table in superimposed relation, endless feeding members arranged along the opposite sides of said table and having parts 25 to engage the several webs of paper simultaneously at a plurality of points to advance the same in fixed relative positions, supporting devices for said endless feeding members mounted on said main frame, between said table and said rolls of paper, and a guard plate interposed between said supporting devices and said rolls of paper to prevent the lower stretches of said endless feeding members from engaging the 30 paper as it feeds from said rolls, and means to actuate said feeding members.

In testimony whereof, I affix my signature in presence of two witnesses.
